Patented Nov. 23, 1976

242,498

WALL-MOUNTED BEVERAGE DISPENSER

Martelle J. Syverson, Albert Lea, Minn., and David B. Syverson and Jon R. Syverson, executors of the estate of Martelle J. Syverson, deceased, assignors to Fountain Industries, Inc., Albert Lea, Minn.

Original design application Jan. 6, 1972, Ser. No. 215,987, now Patent No. 231,575. Divided and this application Oct. 9, 1973, Ser. No. 404,672

Term of patent 14 years

Int. Cl. D15—08

U.S. CL. D15—112

Fig. 1

Fig. 2

Fig. 3

Fig. 4

Fig. 5

FIG. 1 is a front perspective view of a wall-mounted beverage dispenser showing my new design;

FIG. 2 is a top plan view thereof;

FIG. 3 is a front elevation view thereof;

FIG. 4 is an elevational view thereof taken from the end as seen from the right of FIG. 3, the opposite end being a mirror image thereof;

FIG. 5 is a rear elevation view thereof; and

FIG. 6 is a bottom plan view thereof.

This is a division of design application Ser. No. 215,987, filed Jan. 6, 1972, now Pat. No. D. 231,575.

I claim:

The ornamental design for a wall-mounted beverage dispenser, substantially as shown and described.
